(57) **CLAIM**

The ornamental design for a sensor assembly, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, left perspective view of a first embodiment of the claimed design for a sensor assembly;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a top, rear, right perspective view thereof;

FIG. 9 is a top, front, left perspective view of a second embodiment of the claimed design for a sensor assembly;

FIG. 10 is a front view thereof;

FIG. 11 is a back view thereof;

FIG. 12 is a right side view thereof;

FIG. 13 is a left side view thereof;

FIG. 14 is a top view thereof;

FIG. 15 is a bottom view thereof;

FIG. 16 is a top, rear, right perspective view thereof;

FIG. 17 is a top, front, left perspective view of a third embodiment of the claimed design for a sensor assembly;

FIG. 18 is a front view thereof;

FIG. 19 is a back view thereof;

FIG. 20 is a right side view thereof;

FIG. 21 is a left side view thereof;

FIG. 22 is a top view thereof;

FIG. 23 is a bottom view thereof;

FIG. 24 is a top, rear, right perspective view thereof;

(Continued)

FIG. 25 is a top, front, left perspective view of a fourth embodiment of the claimed design for a sensor assembly;
 FIG. 26 is a front view thereof;
 FIG. 27 is a back view thereof;
 FIG. 28 is a right side view thereof;
 FIG. 29 is a left side view thereof;
 FIG. 30 is a top view thereof;
 FIG. 31 is a bottom view thereof;
 FIG. 32 is a top, rear, right perspective view thereof;
 FIG. 33 is a top, front, left perspective view of a fifth embodiment of the claimed design for a sensor assembly;
 FIG. 34 is a front view thereof;
 FIG. 35 is a back view thereof;
 FIG. 36 is a right side view thereof;
 FIG. 37 is a left side view thereof;
 FIG. 38 is a top view thereof;
 FIG. 39 is a bottom view thereof;
 FIG. 40 is a top, rear, right perspective view thereof;
 FIG. 41 is a top, front, left perspective view of a sixth embodiment of the claimed design for a sensor assembly;
 FIG. 42 is a front view thereof;
 FIG. 43 is a back view thereof;
 FIG. 44 is a right side view thereof;
 FIG. 45 is a left side view thereof;
 FIG. 46 is a top view thereof;
 FIG. 47 is a bottom view thereof;
 FIG. 48 is a top, rear, right perspective view thereof;
 FIG. 49 is a top, front, left perspective view of a seventh embodiment of the claimed design for a sensor assembly;
 FIG. 50 is a front view thereof;
 FIG. 51 is a back view thereof;
 FIG. 52 is a right side view thereof;
 FIG. 53 is a left side view thereof;
 FIG. 54 is a top view thereof;
 FIG. 55 is a bottom view thereof;
 FIG. 56 is a top, rear, right perspective view thereof;
 FIG. 57 is a top, front, left perspective view of an eighth embodiment of the claimed design for a sensor assembly;
 FIG. 58 is a front view thereof;
 FIG. 59 is a back view thereof;
 FIG. 60 is a right side view thereof;
 FIG. 61 is a left side view thereof;
 FIG. 62 is a top view thereof;
 FIG. 63 is a bottom view thereof;
 FIG. 64 is a top, rear, right perspective view thereof;
 FIG. 65 is a top, front, left perspective view of a ninth embodiment of the claimed design for a sensor assembly;
 FIG. 66 is a front view thereof;
 FIG. 67 is a back view thereof;
 FIG. 68 is a right side view thereof;
 FIG. 69 is a left side view thereof;
 FIG. 70 is a top view thereof;
 FIG. 71 is a bottom view thereof;
 FIG. 72 is a top, rear, right perspective view thereof;
 FIG. 73 is a top, front, left perspective view of a tenth embodiment of the claimed design for a sensor assembly;
 FIG. 74 is a front view thereof;
 FIG. 75 is a back view thereof;
 FIG. 76 is a right side view thereof;

FIG. 77 is a left side view thereof;
 FIG. 78 is a top view thereof;
 FIG. 79 is a bottom view thereof; and,
 FIG. 80 is a top, rear, right perspective view thereof.
 The broken lines showing the remainder of the sensor assembly depict environmental structure and form no part of the claimed design.
